CLAIM

The ornamental design for a steam trap insulator, as shown and described.

DESCRIPTION

FIG. 1 is a perspective view of the steam trap insulator showing my new design in a flat configuration;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof; and,

FIG. 8 is a perspective view of the steam trap insulator as shown on a typical steam trap (shown in phantom). The typical steam trap shown in FIG. 8 is for reference only and is not to be considered a part of the present invention.
